RETURN BEND HOUSING

Frederick E. Key, East St. Louis, Ill., assignor to
 Key Boiler Equipment Co., East St. Louis, Ill., a
 corporation of Missouri

Application August 21, 1929, Serial No. 387,346

8 Claims. (Cl. 285—20)

This invention relates to return bend housings, and has special reference to housings and associated parts for connecting and forming satisfactorily leak-proof communication between adjacent tubes.

Objects of the invention are to provide means for connecting and providing communication between adjacent tubes and comprising sleeves or tubular elements secured to the ends of the tubes in cooperative relationship in such a way that they cannot twist or move laterally relatively to each other to any substantial extent but are capable of relative longitudinal movement as required to provide tolerance and compensate for certain inequalities in the associated parts of the structure, or inequalities in the arrangement or location of the ends of the tubes; to provide means for holding a return bend in cooperative relationship with said sleeves or tubular elements by holding devices, including housing members engaging and partially or completely enclosing said sleeves or tubular elements; to provide a structure of this type and arrangement permitting said sleeves or tubular elements and the return bend to be made from the same metal, or from metals having approximately the same coefficient of expansion, and the housing members to be made from a different and less expensive metal; and to provide a novel and efficient cooperative relationship of the housing members with the remaining elements of the device, whereby the duration of satisfactory use and efficient functioning of this device is extended much longer than in the case of many devices now in general use.

Another object of the invention is to provide an improved return bend housing and cooperating members functioning efficiently to maintain impervious and leak-proof joints with the connected tubes indefinitely and irrespective of the wide variations in temperature, thus greatly reducing the fire and other hazards incident to the use of this invention in connection with oil stills and other mechanisms.

Various other objects and advantages of this invention should be apparent from the following description, reference being made to the annexed drawings, in which—

Fig. 1 is a view with parts in section and other parts in side elevation illustrating the invention in connection with adjacent tubes.

Fig. 2 is a sectional view approximately on the line 2—2 of Fig. 1.

Fig. 3 is an end plan view of the sleeves or tubular elements adapted to be attached to adja-

cent ends of adjacent tubes and having connection with the return bend of the device.

Fig. 4 is an inner end elevation of one of the housing members.

Fig. 5 is a cross sectional view of one of the housing members on the line 5—5 of Fig. 1.

Fig. 6 is a plan view of a tie member mounted in connection with the tubes with which the present invention is connected.

In the embodiment of the invention shown, a sleeve or tubular element 1 is connected with an end of each tube that is to be connected with an adjacent end of an adjacent tube. One of these sleeves 1 is provided with a laterally extended ear or lug 8 located at the side of a similar laterally extended lug 9 in connection with the cooperating sleeve. In the specific construction shown (Figs. 2 and 3), each sleeve 1 has laterally extended ears or lugs 8 and 9, one of these ears or lugs on each sleeve extending between and in close contact with the ears or lugs on the other. This constitutes an embodiment of means for interlocking the two sleeves and preventing substantial twisting or lateral movement of either sleeve with respect to the other. After assembly, the ears or lugs 8 and 9 lie side by side, and have slots 10 in approximate alinement. A bolt 11 extends through the slots 10 and prevents separation of the pair of sleeves connected thereby. Since the slots 10 are longer than the diameter of the bolt 11, the two sleeves are capable of relative longitudinal movement as required to provide tolerance and compensate for certain inequalities in associated parts of the structure, or inequalities in the arrangement or location of the ends of the tubes.

The outer end of each sleeve 1 is formed with a tapered bore 12, which receives, and the wall of which constitutes, a joint forming seat for the tapered end 13 of a U-shaped or arcuate tubular return bend 14. Opposite portions of the return bend 14 are provided with shoulders 15, each having in its outer side a recess 16 receiving the abutting end 17 of a securing set screw 18. The set screws 18 are screwed through threaded holes 45 in plates 19 engaged with the adjacent ends of respective housing members 20. The outer end of each housing member 20 is arcuate or approximately U-shaped in cross section and is formed with an inwardly extended flange 21 against which an abutting portion 22 of the cooperating plate 19 engages. The housing members 20 are also provided with openings 23 into which project parts 24 formed on the plates 19. This construction, comprising the parts 24 extending into the

openings 23, constitutes an interlock to prevent the plates 19 from turning when the securing set screws 18 are rotated.

The inner end of each housing member 20 may be in the form of an annulus 25 receiving a sleeve 7 and provided with an inwardly extended flange 26 engaging the inner end of said sleeve. The diameter of the sleeve 7 is less than the inside diameter of the annulus 25, so that said sleeve 7 and said annulus 25 may expand and contract relatively and freely without interference of either with the other. This construction constitutes means permitting the return bend 14 and the sleeve 7 to be made from the same metal or from metals having approximately the same coefficient of expansion, while the housing members 20 may be made from a different and less expensive metal having a different coefficient of expansion without the least sacrifice in the efficiency and durability of the device. Adjacent to and extending outwardly from the annulus 25 each housing member is formed with a longitudinal opening 27 through which the ears or lugs 8 and 9 in connection with the sleeves 7 extend to interlocking connection, as shown and described.

The opening 28 at the inner portion of each sleeve 7 is concentric with the axis of the tapered bore 12 and receives one end of a tube 29. Accordingly, when the sleeves 7 and the return bend 14 are assembled in connection with each other and with the tubes 29, a continuous passage from one of said tubes 29 to the other of said tubes 29 is provided.

The sleeves 7 may be attached to the tubes 29 either by rolling or expanding the ends of the tubes within the sleeves by means of a suitable tool to obtain the attachment shown in Fig. 1; or the sleeves may be screwed on the tubes. It is possible to screw the sleeves 7 on the tubes and to obtain a satisfactory connection when said sleeves and the tubes have the same coefficient of expansion but, if the coefficient of expansion of the sleeve is different from that of the tube, a screw threaded connection is not satisfactory because the connection may become loose when there are changes in temperature.

The tubes 29 may be held from substantial spreading apart or moving toward each other by a tie member 30 having openings 31 through which said tubes extend. As shown, the tubes 29 extend through a head 32 having openings 33 of slightly larger diameter than the outside of the tubes. In this assembly, the tie member 30 performs the useful functions indicated.

In assembling and mounting my invention for use, the tie member 30 is placed on the adjacent ends of a pair of adjacent tubes 29 which extend through openings in the head 32. The openings 31 permit the tie member 30 to slide along the tubes to proper position. The annulus 25 of a housing 20 is then applied about the end of each tube and a sleeve 7 in each annulus 25 is attached to the adjacent end of the tube either by expanding the tube within the sleeve or by screwing the tube in the sleeve. In this position of the sleeves 7, the ear or lugs 8 and 9 on the respective sleeves are in overlapping and sidewise abutting relationship, thus preventing substantial relative twisting or lateral movement of the sleeves. The bolt 11 is then passed through the slots 10 and secured in this position.

After the sleeves 7 have been attached to the adjacent ends of adjacent tubes 29, the tapered ends 13 of the return bend 14 are placed in and against the joint forming seat 12. The plates 19

are then mounted in position with the parts 24 thereof extending into the openings 23 in the housing members 20. The set screws 18 are then screwed inwardly against the bottoms of the recesses 16 to apply the pressure necessary to force the tapered ends 13 of the return bend into and against the joint forming seats 12 and thereby obtain an extremely tight connection and joint. This clamping adjustment of the screws 18 causes the flanges 26 to abut securely against the inner ends of the sleeves 7, and the ends 13 of the return bend to be forced into close sealing engagement with the seat 12. Should there be slight inequalities in the dimensions of the tapered ends 13 or the seats 12 or slight inequalities in the arrangement or location of the ends of the tubes, the necessary tolerance to obtain perfectly tight joints irrespective of these inequalities is obtained by this improved construction and arrangement shown, because neither the sleeves 7 nor the housing members 20 are integrally united. Necessary longitudinal or axial adjustment of the sleeves 7 to provide tolerance and compensate for slight inequalities in the arrangement or location of the ends of the tubes is permitted by the slot 10.

It must also be apparent that my invention prevents lateral or twisting movement of the sleeves with respect to each other and that there is no twisting strain exerted against the return bend 30 when said bend is placed and clamped in position. In the case of devices heretofore used, it has occurred that when the return bends were removed after a still had been in use, it was found that the return bends on being replaced did 35 not assume the same relative positions with respect to the tubes that they occupied before they were removed. By eliminating lateral and twisting movement of the sleeve with respect to each other, this difficulty is avoided. It has also occurred that the tubes warp and strain the return bends, so that after the return bends have been removed and replaced a number of times in different positions, they are subjected to such strains in different directions that the return 40 bends eventually break or become useless. These twisting actions and strains produce a damaging crystallizing effect on the return bends. My invention completely eliminates these difficulties and prevents the application of twisting strains 45 to the return bends either by the warping of the tubes, or otherwise.

I claim:—

1. A return bend fitting comprising a plurality of adjacent sleeves; longitudinally extending 55 spaced tongues carried by said sleeves for interlocking them together to prevent relative lateral and twisting movement therebetween; means for securing said tongues together to permit longitudinal movement of the sleeves relatively of 60 one another; a return bend; a housing about each sleeve; and means for securing said return bend in said housing.

2. A return bend fitting comprising a plurality of sleeves having longitudinally extending 65 tongues for interlocking said sleeves together to prevent lateral and twisting movement of one sleeve relative to another; means for securing said tongues together to prevent separation of the latter and permitting longitudinal movement 70 relatively between said sleeves; a return bend element; a housing partially surrounding each of said sleeves; a tube secured in each of said sleeves; and means for securing said return bend element in said housing to communicate with 75

- said tubes, the ends of said return bend element secured in said sleeves.
3. A return bend fitting comprising a plurality of sleeves having longitudinally extending 5 tongues and grooves for slidably interlocking the same together to permit longitudinal movement only between said sleeves; means through said tongues to prevent separation of the sleeves; a return bend removably secured in said sleeves; a tube secured in each of said sleeves; a housing about each of said tubes and a portion of each 10 of the sleeves and partially surrounding the remaining portion of said sleeves and projecting therebeyond; and means removably carried by 15 said housing for securing said return bend in position.
4. A return bend fitting comprising a plurality of sleeves having an interlocking tongue and groove longitudinally therebetween to slidably interlock the same together to permit only longitudinal movement between said sleeves; means through said tongue and groove connection to prevent separation of said sleeves; a return bend removably secured in said sleeves; a tube secured 20 in each of said sleeves; a housing surrounding each of said tubes and a portion of each of said sleeves and partially surrounding the remaining portion of said sleeves and projecting beyond the latter, said housings having an inwardly extending flange on their lower ends and against which the sleeves may seat; and means including a removable plate carried by said housings for securing the return bend in position.
5. A return bend fitting comprising a plurality of sleeves provided with longitudinally extending means for slidably interlocking them together and permit only longitudinal movement therebetween; a return bend removably secured 25 in said sleeves; a housing surrounding a portion
- of each sleeve and projecting therebeyond; and means mounted on each of the housings to engage the return bend for securing the latter in said sleeves.
6. A return bend fitting comprising a plurality of sleeves having longitudinal tongues and grooves therebetween to slidably interlock said sleeves together to permit longitudinal movement only between the same; means to prevent separation of said sleeves; a return bend; a housing having an inwardly extending flange adjacent one end and provided with a longitudinal opening through its wall thereabove, one of said sleeves positioned in each of said housings; and a plate and screw removably carried by each of 10 15 said housings to secure the return bend therein in said sleeves.
7. The combination with a return bend adapted to connect a plurality of tubes; of a fitting therefor comprising tubular elements adapted to 20 be connected to the tubes; housing sections independent of said tubular elements and loosely encircling the latter; detachable means mounted in said sections to engage said return bend; and co-acting portions on said tubular elements that 25 prevent twisting movement between the same but permit a slight relative longitudinal movement between said tubular elements.
8. The combination with a return bend; of a fitting therefor comprising sleeves each engaging one of a plurality of tubes; housing sections surrounding said sleeves; means on said housing sections for holding the return bend in operative 30 relationship with said sleeves; and means at the sides of said sleeves and extending through said 35 housings preventing relative twisting movement between said sleeves but permitting a slight longitudinal movement therebetween.

FREDERICK E. KEY.
